UNITED STATES PATENT OFFICE.

WALTER D. DRAKE, OF SANTA FÉ, MISSOURI.

BREAST-STRAP HOOK.

SPECIFICATION forming part of Letters Patent No. 333,734, dated January 5, 1886.

Application filed June 10, 1885. Serial No. 168,275. (No model.)

To all whom it may concern:

Be it known that I, WALTER D. DRAKE, of Santa Fé, in the county of Monroe and State of Missouri, have invented a new and Improved Breast-Strap Hook, of which the following is a full, clear, and exact description.

My invention consists, principally, of a hook to be attached to the breast-strap or breast-strap slide or guard of harness for facilitating the work of attaching the neck-yoke to and detaching it from the breast-strap.

The invention also consists in pivoting the hook to the breast-strap slide or guard, and in providing the hook with a retaining-ring 15 for locking the ring of the neck-yoke in the hook, the retaining-ring being provided with a loop to receive the holdback-strap of the harness.

Reference is to be had to the accompanying 20 drawings, forming part of this specification, in which similar letters of reference indicate corresponding parts in both the figures.

Figure 1 is a front elevation of my breast-strap hook attached to a breast-strap slide or 25 guard; and Fig. 2 is an inverted plan view of the same, showing the preferred construction of the retaining-ring, the same being in position for closing the hook.

A represents the hook. This may be attached directly to the breast-strap of the harness, or it may be hinged or pivoted by bolt 30 a to the breast-strap slide or guide B. The hook A has the retaining-ring C applied to it for closing the entrance to the hook, as shown in the drawings, for retaining in the hook the neck-yoke ring D. The retaining-ring C is attached to the hook A by being passed through 35 the hole b, made in the hook, as shown in Fig. 1, and the ring in this instance is notched, as shown at d, so that when the ring is turned to bring the notch d in line with the outwardly-projecting part e of the hook the ring may be 40 lifted to open the hook, or, being open, may be lowered below the point e to close the hook, and turned to bring notch d out of line with 45 point e, thus causing the ring to lock with the point e to securely retain the ring D in the

hook, as it is almost impossible for notch d to get back into line with point e after the slack in the holdback-strap is taken up by hitching 50 the traces. In most cases the retaining-ring C, besides being formed with notch d, will also be formed with the loop f, into which the holdback-strap of the harness may be buckled, thus avoiding the necessity of placing the holdback-strap over the neck-yoke, as is the usual practice.

In use the hook A will be attached to the breast-strap with the point e standing away from the tongue, so that the ring of the neck-yoke may be conveniently dropped into and lifted out of the hook in hitching up and unhitching the team, and by the use of the hook much time is saved in the labor of hitching up and unhitching the team, as the retaining-ring 65 C has simply to be operated to open or close the hook and the hook attached to or detached from the neck-yoke ring, both of which may be quickly and easily done without undoing the breast-strap or disturbing the holdback-strap. Besides this the loop f always keeps the holdback-strap at the end of the neck-yoke, so the horses may back a load or hold it back in going down grade with the best 70 advantage, and the hook is perfectly secure 75 and reliable in holding the ring D.

Having thus described my invention, what I claim as new, and desire to secure by Letters Patent, is—

1. The guard B and the hook A, in combination with the retaining-ring C, formed with the loop f, substantially as and for the purposes set forth.
2. The guard B, having the hook A attached to it, in combination with the retaining-ring 85 C, notched at d and formed with the loop f, the hook A being formed with the outwardly-projecting point e, substantially as and for the purposes set forth.

WALTER D. DRAKE.
